METHOD AND APPARATUS FOR ESTABLISHING ELECTRICAL CONTACT TO A PLURALITY OF WIRES

Renn Zaphiropoulos and Howard R. Patterson, Oakland, Calif., assignors to Chromatic Television Laboratories, Inc., New York, N. Y., a corporation of California

Application July 11, 1955, Serial No. 521,013

4 Claims. (Cl. 313—78)

This invention relates to a method and apparatus for establishing electrical contact to each of one or more sets of electrically separable conductors. The invention is intended to improve upon ways and means for making electrical connections to each of one or more electrically separable sets of conductors on grids designed for use near the target area of color television tubes.

In the design and construction of color television tubes wherein one or more color-control and focusing grids are employed near the target area, it is often desired to have grid conductors formed into two electrically separate sets. In the case of a single gun color television tube employing color switching near the target it is customary to employ a grid structure of this general type to provide so-called "color switching" and to serve as one component of a series of electron lens elements. In certain types of such tubes, a large number of very narrow phosphor strips are deposited on a target. Each of these phosphor strips is of a composition which emits a selected color of light when impacted and excited by a scanning electron or cathode-ray beam. In the present art, a tricolor additive color system is usually used, that is, three different kinds of phosphor strips are deposited on the target, each adapted to emit a different color of light when impacted. The three colors so emitted are chosen so that they may readily be combined and color balanced to produce white light. The three colors chosen will also produce, by various combinations the other colors of the color spectrum, within certain limitations not material here. In color television tubes employing grids near a target area for deflecting the electron beam with respect to target area strips such as those hereinbefore described, separate sets of grid conductors which are electrically distinct from each other are necessary. Since the phosphor strips in the aforementioned types of tubes are arranged in repeating color cycles of the order of a single picture element in width for each such cycle, and since the grid structure or micro-deflecting means has a spacing between the adjacent and deflecting conductors of the order of one-half each such repeating color cycle, a great number of extremely accurately positioned, tautly held and vibration free grid conductors are necessary. Furthermore, since the color control switching must be applied during the time the scanning beam is traversing a lineal distance of the same order of magnitude as the distance the grid conductors are spaced apart, the color control or switching signals are necessarily relatively high in frequency, and in fact lie in what is ordinarily termed the radio frequency or RF range.

The invention herein relates to a novel method and fixture for making connection to each of several electrically separable sets of conductors on a grid designed for use near a target area where the grid conductors have previously been mechanically secured to the grid frame or reference member. A number of problems arise in making simultaneous connections to a large number of such conductors. For example, a low resistance electrical contact is desired to each and every conductor in each

2

set. This electrical connection to each conductor should exhibit the aforementioned low electrical resistance at the switching frequencies employed, which, as mentioned hereinbefore, are relatively high and lie in the radio frequency range. It is also desirable to have the electrical resistance as nearly uniform as possible from one conductor to any other conductor in the set. In addition, various other features are necessary or desirable, as will appear hereinafter.

Another problem encountered in the design and construction of grids such as those described herein is that of shielding the connecting and securing structure. The invention herein results in a connection to the grid wires which is movable and solves various problems relating to shielding as will appear hereinafter.

It is accordingly a principal object of the invention to provide a method and fixture for establishing electrical contact to a plurality of wires which will provide relatively low electrical resistance at R. F. frequencies to each of such wires, which resistance will be uniform for all the wires contacted and which will not change or vary with age. Another principal object of the invention is to provide a method and fixture for establishing electrical contact to each of said plurality of wires which is simple, economical, and efficient. Another object of the invention is to provide a method and fixture which results in a contacting strip assembly wherein shorts and opens may be easily located and cleared.

Another object of the invention is to provide a means for contacting a plurality of wires in each of several sets of conductors which is flexible in relation to the various design considerations encountered in assembling a grid adjacent to the target area of color television tubes. More specifically in this connection, it is among the objects of the invention to provide a method and fixture for making grid connections which results in a contacting structure wherein a connection may be on either end of the grid and to one or more variously located points on either or both of such ends, a structure, furthermore, which is movable, both with respect to the grid and grid frame and with respect to the other contacting structures, and a structure which may be easily electron-beam and radiation-shielded, thus avoiding the pick-up of stray fields or beams which might interfere with the operation of the grid or grids to which it is connected. It is also an object of the invention to provide a grid contacting structure of such a form that both the contacting structure and the mechanical securing means may be simultaneously shielded as aforementioned. An object of the invention is to allow simultaneous electrostatic shielding of the contacting structure and mechanical securing means.

Another principal object of the invention is the provision of a method and fixture which is adaptable to automatic and semi-automatic techniques of production. A further object of the invention is the provision of a method and fixture which allows rapid and efficient assembly. Also an object of the invention is the provision of a method and fixture having numerous other objects and advantages, which will become apparent to those skilled in the art from the specification herein.

In the invention, electrically separable sets of conductors, which have previously been physically secured in a desired accurate configuration relative to each other within a grid area proper, as defined by the grid supports, are separated into the desired number of sets of conductors, ordinarily two sets. In the usual case, which is that of grids wherein the sets of grid conductors within the grid area proper all lie in one plane, or nearly within one plane, the sets of grid conductors are separated adjacent to each end of the grid area into sets of conductors lying in planes substantially parallel to and above

each other. Temporary means may be employed to hold the physically separated sets of electrically separable conductors distinct from each other pending further steps of the method. In a preferred method of the invention, conducting metallic strips of a metal other than that employed for the grid conductors are then affixed to heat conducting positioning parts of a jig or fixture, that is, to an anvil, to one or more spacers, and to a clamping piece. In the cases where there are only two sets of conductors to be separated only one spacer is necessary. The separated sets of grid conductors are arranged to be included within the conducting strips so mounted on the anvil, spacer and top clamp of the fixture and all the pieces are clamped in position. The anvil, spacer, and top clamp are all composed of a heat conducting material, so as to dissipate the heat generated during the welding operation and thereby make a desirable electrical and mechanical connection and also to confine the weld to a small section or "bead" near the edges of the strips. After the conductors have been clamped between the strips mounted on the heat conducting parts, a welding means, preferably of the inert gas-shielded type, is run along the outermost junction of each of the pairs of strips, thereby joining the strips and the conductors in a welded seam, securing the grid conductors both mechanically and electrically to the joined strips. Due to the variation in the total thermal conductivity of each of the various cross-sections involved, and the effect of the anvil, spacer and top clamp, in combination with the dissimilar metals being joined, an irregular ball-shaped connection is made at the end of each conductor to the strips. This connection is so formed that it insures excellent uniform low resistance R. F. electrical contact to each of the grid conductors, and is also trouble-free for very long periods of time. R. F. losses are also at a minimum in this construction. After the weld has been completed, the anvil, spacer, and top clamp may then be removed, as well as the temporary means, if any, used to keep the sets of conductors physically separated. In the preferred form of the invention, a volatile glue is used to affix the metallic conducting strips to the anvil, spacer, and top clamp, and the metallic strips are accordingly automatically released from the fixture by the welding operation. The welding operation also preferably trims the excess of the grid conductors extending beyond the metallic strips automatically.

The invention will be more fully understood, and further objects and advantages will appear in connection therewith, by the reference to the following description read in connection with the accompanying drawings, wherein:

Fig. 1 is a diagrammatic view, partly in cross-section, illustrating a preferred form of the fixture for the practice of the method of the invention, with the end portion of a typical grid frame mounted therein; and

Fig. 2 is a cross-sectional view in elevation of said end portion of the frame, showing the completed grid connection made by the method and in the fixture of the invention.

Turning now to a consideration of the figures of the drawings, the same numbers have been used to designate the same parts throughout. In Fig. 1, a grid frame 49 having a grid support 51 for the fastening of grid conductors 11 by a mechanical means 31, such as a ceramic cement or silica frit combination, is placed in fixture or jig 10. The form of frame 49 and support 51, as well as the mechanical holding means 31, are of course, only illustrative, and other forms of these components may profitably employ the method and fixture of the invention. The ceramic cement, silica frit combination or other means 31 used to mechanically secure the conductors 11 must, of course, be such that the various sets of grid conductors 13, 15 may be electrically isolated from each other.

Fixture 10 is comprised of a bridge assembly 45 75

4
mounted on base 47 by screws 43 or other means and having a top or bridging portion 41 lying in a plane parallel to that of the base 47. Arm 35 is mounted on the bridge 45 by means of pivot 39 and supports top clamp 17. Suitable securing means, illustratively the screw 37, serve to secure top clamp 17 in position when the fixture 10 has been assembled prior to the welding operation. Also attached to the bridge 45 is an optional shield 33 designed to prevent damage to the grid conductors 11 during the welding operation. Spacer 19 and anvil 21, together with clamp 17, hold the set of conductors 13 between detachable metallic strips 23 and 25 and the set of conductors 15 between detachable metallic strips 27 and 29, in position to effect a weld by welding torch 53. 15 Metallic strips 23, 25, 27 and 29 are of a metal other than that employed for the grid conductors 11. Spacer 19 is also preferably of a metal other than strips 25 and 27 to avoid any tendency to become welded thereto. In the application of the method and fixture of the invention, grid frame 49, having electrically separable conductors 11 as described above, is mounted in place on jig or fixture 10. The conductors 11 are separated into the desired sets of conductors 13 and 15 either prior to or after such mounting. Temporary separating means 25 may be employed to hold the sets of conductors 13 and 15 separated until the anvil 21, spacer 19, and top clamp 17 are applied. For example, a narrow glass tape may be placed between the sets of wires 13 and 15 so that the alternate wires forming the one set 15 are below the tape and the rest of the wires 13 are above it. The ends of the wires in set 13 and in set 15 may then be sandwiched between two sets of masking tape to keep them distinct and easily separable. Alternatively, the wires may be separated and immediately placed between the anvil 21, spacer 19 and top clamp 17. A metallic strip 23 is temporarily affixed to top clamp 17, metallic strips 25 and 27 are affixed to spacer 19, and metallic strip 29 is affixed to anvil 21. A glue which is easily volatilized is preferred for this operation, since such a glue will be volatilized during the welding operation and the strips mounted on clamp 17, spacer 19 and anvil 21 will be released without further effort. Other means of securing the strips may, of course, be used. Alternatively, strips 23, 25, 27 and 29 may be directly applied to the sets of grid conductors 13 and 15 during the initial physical separation, in lieu of, for example, the masking tape mentioned hereinabove.

Top clamp 17, spacer 19, and anvil 21 are all made of metal or other material with a relatively high coefficient of thermal conductivity so as to readily conduct the heat involved during the welding operation, thereby performing as chill rings and confining the weld to the edges of the metallic strips, and, in addition, helping to create a desirable type of electrical connection to conductors 11. After the grid conductors 11 have been clamped in place with each set of conductors 13, 15 encompassed respectively between a pair of strips 23—25, and 27—29, screw 37 or its equivalent is operated to clamp the assembly in position. After the assembly has been so clamped, welding means 53, preferably of the inert gas-shielded type, such as "Heliweld" or "Heliarc," is caused to operate and during such operation to move along adjacent to or in contact with the outermost junction of the pairs of strips 23, 25 and 27, 29 effecting the welds of each pair of said strips and the respective sets of conductors 13, 15 included therebetween.

It will be noted from the above that the method of the invention may be practiced by hand, since the anvil 21, spacer 19, and clamp 17 may be provided with a handle or holding means and the welding torch operated manually. During the welding operation, and grid wires 11 are preferably protected from damage by a shield 33. The welding operation, in addition to permanently joining the strips 23, 25 with the set of conductors 13,

and strips 27, 29 with the set of conductors 15, trims off the excess wires in sets 13 and 15.

Ordinarily the sets of grid conductors 13 and 15 will be separated by a relatively small distance, and spacer 19 will accordingly be of limited dimensions. For this reason, spacer 19 is preferably of a metal other than that of strips 25 and 27, and preferably such metal has a relatively high thermal capacity, thereby avoiding any tendency to become welded to strips 25 and 27 during the welding operation and permitting ready removal thereafter. Anvil 21 and top clamp 17 may easily be made of larger dimension and accordingly may be of the same or of a different metal than strips 23 and 29.

Referring now to the cross-sectional view of Fig. 2 wherein the end portion of the frame 49 is shown in elevation it will be seen to illustrate the appearance of frame 49 after the welding operation has been completed, resulting in connection to conductors 13 by strip assembly 57 and conductors 15 by strip assembly 59. In Fig. 2, frame 49 is shown removed from the fixture 10. Support 51 and the mechanical holding means 31 physically securing grid conductors 11 are illustrated as before. In addition, a combination electron beam and radiation shield 55, secured to support 51 by screw 61, is shown. Other forms of shield 55 may be employed, and fastened by other means, but it is a special object and advantage of the invention herein that the assemblies 57 and 59 are movable sufficiently so that shield 55 may be arranged easily and simply to cover both the assemblies 57 and 59 and the mechanical securing means 31, forming an effective shield for both.

Attention is especially directed, at this point, to the novel character of the electrical connection obtained by the method and fixture of the invention. A portion of the weld, including the connection, is shown in cross-section at 57 and at 59 in Fig. 2. It will be noted in Fig. 2 from an inspection of the contacting strip assemblies 57 and 59 that the ends of the conductor 11, after the weld has been completed, are irregularly ball-shaped in character.

This electrical and mechanical connection is not affected by the movement of contacting assemblies 57 and 59 to allow the imposition of shield 55. Shield 55 extends as shown in Fig. 2 to cover both the contacting assemblies 57 and 59 and the securing means 31. Shield 55 thereby functions as a radiation shield and a beam shield, and additionally as an electrostatic shield. One of the electrostatic shielding effects of shield 55 is to keep securing means 31 from charging and discharging and giving undesirable optical and electrical effects such as electrostatic glows. The shielding as aforementioned of course does not affect the efficiency of the desirable ball-shaped connections to grid conductors 11 in assemblies 57 and 59.

The reason the desired shape and efficient electrical connection are obtained may be best understood by a consideration of Fig. 1. Dissimilar metals are used for the strips 23, 25, 27 and 29 as compared to the grid conductors 11. As the weld is made, more heat is supplied to the strips forming the contacting strips 57 than to the grid conductors 11 included between said strips 57 because of the relative amounts of area of each exposed to the welding means. This heat, however, is confined mainly to the edges of the strips, due to the cooling or chilling effect occasioned by the relatively high thermal conductivity of anvil 21, spacer 19 and top clamp 17. The strips 23, 25, 27 and 29 are accordingly, during the first instants of the welding operation, rendered more completely in a fluid condition than the ends of the grid conductors 11, and the result is that the ends of grid conductors 11 tend to become ball-shaped in character.

This shaping effect is enhanced by employing a metal having a relatively high thermal conductivity for the strips 23, 25, 27 and 29. Aluminum is the metal pre-

ferred, both for this reason and because of its other advantages, such as low electrical resistance and light weight. In fact, contacting strip assemblies 57 and 59 comprised of aluminum strips 23, 25 and 27, 29 need no further support than that afforded by the separated sets of grid conductors 13 and 15. Other metals, such as silver, may also be used for the strips 23, 25, 27 and 29. Grid conductors 11 may be of stainless steel, and the method and fixture of the invention has been highly successful with the grid conductors 11 composed of this material. However, insofar as the invention herein is concerned, other materials are also satisfactory for grid conductors 11, and, with most such materials, the additional effects occasioned by the relative thermal conductivities will still obtain if strips 23, 25, 27 and 29 of aluminum are employed since aluminum has relatively high thermal conductivity as compared to most metals. Metals other than aluminum may also be used for the contacting strips 23, 25, 27 and 29, even those of relatively low thermal conductivities, since, as pointed out hereinabove, the desirable electrical connection arises from the effect of the total heat supplied and the chilling or limiting of the fixture 10, as well as from the effect due to the inherent thermal conductivity of the metals of the strips 23, 25, 27 and 29 and the grid conductors 11.

Arc welding is the preferred form of welding, although other types of welding may be employed, such as resistance welding. Inert gas-shielded welding is the preferred form of arc welding. Aluminum, for example, may be welded without a flux with the inert gas-shielded method. When aluminum is welded by this method, an A. C. voltage which has poor regulation and a high open circuit value, or, alternatively, which has superimposed high frequency, is desirable for arc stabilization. The shielding gas employed in such a case may be helium or argon, but is not limited thereto. In a specific application of the method and fixture of the invention, helium gas-shielded or "Heliarc" welding has been found to be very satisfactory. The particular values employed are 41 volts at 13 amperes, for welding aluminum strips to stainless steel grid wires.

The method and fixture of the invention having been described in terms of specific embodiments hereinabove, the invention is to be limited only by the following claims.

We claim:

1. In a grid especially adapted to be used near the target area of a color television tube, a grid contacting assembly for making electrical connections to at least one electrically separable set of grid conductors which have previously secured in a desired physical configuration by a mechanical supporting means on said grid comprising a plurality of extensions of the grid conductors forming said electrically separable set, said extensions protruding beyond said mechanical supporting means; a pair of strips of a metal other than the metal of the grid conductors arranged oppositely of each other to include said extensions; and a seam weld joining said pair of strips and said grid conductor extensions at the outermost junction thereof to form said contacting assembly.

2. The grid contacting assembly of claim 1 comprising in addition a shielding member arranged to simultaneously cover both said mechanical supporting means and said contacting assemblies to provide a shield from electron beams and radiation for said mechanical securing means and said contacting assemblies.

3. The grid contacting assembly of claim 1 wherein said grid conductors are stainless steel and said strips are aluminum.

4. A grid construction especially adapted to be used near the target area of color television tubes comprising: a frame member including a support member; a plurality of grid wires; means including said support member to mechanically secure said grid wires in a desired configuration relative to said frame member; extensions of said

grid wires protruding beyond said support member; a contacting strip assembly comprising a pair of strips of a metal other than that of said grid wires arranged transversely of and on either side of said extensions, said strips and said wires being joined in a unitary welded mass at the outermost edges of said strips; a shielding member disposed to shield said contacting strip assembly, grid wire extensions and mechanical securing means; and connecting means for establishing electrical contact to said contacting strip assembly.
